CLAIM

I claim the ornamental design for a computing device, as shown and described.

DESCRIPTION

FIG. 1 is a front perspective view of a computing device;
FIG. 2 is a right side view thereof;
FIG. 3 is a left side view thereof;
FIG. 4 is a front view thereof;
FIG. 5 is a rear view thereof;
FIG. 6 is a top view thereof;
FIG. 7 is a bottom view thereof; and,
FIG. 8 is a front perspective view of the computing device of FIG. 1 in an alternative orientation.

The broken lines in the drawings are for illustrative purposes only and form no part of the claimed design.
